UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed June 3, 1929. Serial No. 367,895.

This invention relates to mining machines, and more particularly, but not exclusively, to coal mining machines of the flexibly fed, continuous cutter type.

5 An object of this invention is to provide an improved coal mining machine. Another object is to provide an improved coal mining machine having improved feeding mechanism. Another object is to provide an improved coal mining machine of the flexibly fed, room 10 and pillar type having improved feeding mechanism including relatively rotatable feed operating and controlling members and cooperating flexible feeding means, and improved driving and controlling means for the 15 said feed operating and controlling members. Still another object is to provide an improved mining machine of the aforesaid type having improved feeding mechanism including relatively rotatable feed operating and controlling winding drums and cooperating feeding and controlling cables, and improved driving and controlling means for each drum. Another object is to provide in a mining machine of the aforesaid type separate driving and controlling means for each winding drum whereby the drums may be 20 simultaneously or separately driven at either a relatively slow speed or a relatively high speed. Yet another object is to provide in a mining machine of the aforesaid type improved feeding mechanism including separate driving and controlling means for each winding drum whereby the drums may be 25 rotated in winding direction either separately or simultaneously at relatively low speed or at relatively high speed, or may rotate in unwinding direction under various degrees of frictional resistance or freely. Another object is to provide improved guiding means 30 for the flexible feeding means of such a machine. These and subsidiary objects of this invention will, however, subsequently more fully appear.

In the accompanying drawings there is 35 shown for purposes of illustration one form

which the invention may assume in practice.

In these drawings,—

Fig. 1 is a top plan view of an illustrative embodiment of the improved mining machine, the cutter bar being partially broken 55 away.

Fig. 2 is a side elevational view of the machine shown in Fig. 1.

Fig. 3 is a rear end elevational view of the improved mining machine.

Fig. 4 is an enlarged top plan view, partially shown in horizontal section, illustrating the improved feeding mechanism.

Fig. 5 is a central, longitudinally extending, vertical sectional view taken substantially on line 5—5 of Figs. 1 and 4.

Fig. 6 is a transverse vertical sectional view, with parts shown in elevation, taken substantially on line 6—6 of Figs. 2 and 5, parts being omitted to facilitate illustration.

Fig. 7 is a transverse vertical sectional view, with parts shown in elevation, taken substantially on line 7—7 of Fig. 4, parts being omitted to facilitate illustration.

Fig. 8 is a detail sectional view illustrating the cutter chain drive clutch and the operating mechanism therefor.

Fig. 9 is a fragmentary side elevational view of the mechanism shown in Fig. 8.

Fig. 10 is a detail sectional view illustrating the improved operating means for the feed controlling clutches, parts being shown in top plan.

Fig. 11 is a detail sectional view taken on line 11—11 of Fig. 10.

Fig. 12 is a detail sectional view taken on line 12—12 of Fig. 2, illustrating the improved cable guiding means.

Fig. 13 is a detail sectional view illustrating the swing arm lock.

Fig. 14 is a detail sectional view illustrating one of the rear guide sheaves.

In this illustrative embodiment of the invention there is shown a coal mining machine of the flexibly fed continuous cutter, room and pillar type generally comprising a frame or body 1 adapted to rest upon and slide in any direction over the mine floor. Rigidly secured within this frame and projecting forwardly lengthwise thereof is an

100

elongated horizontal plane cutter bar 2 about the outer edges of which an endless cutter bit carrying cutter chain 3 is mounted. The machine is adapted to be fed bodily laterally across the coal face to insert a horizontal 5 kerf at the base of the mine wall and guided during such feeding movement by means of relatively rotatable feed operating and controlling members 4 and 5 arranged at opposite sides of the machine at the rear end there- 10 of on transverse axes and cooperating respectively with flexible feeding elements 6 and 7. The feed operating and controlling members 4 and 5 and their cooperating flexible feeding elements 6 and 7 are herein in the form 15 of winding drums and cooperating feed cables or ropes. The frame or body 1 comprises a bed frame 8 supported on a bottom plate or shoe 9, the latter having a smooth bottom plane surface 10 upon which the ma- 20 chine rests and slides. The bed frame 8 supports at the front end thereof a motor section 11 arranged directly above the rear end of the cutter bar 2. Arranged at the rear of the motor section 11 and likewise supported 25 by the bed section 8 is a frame section 12 housing the driving mechanism for the cutter chain 3 and the winding drums 4 and 5, as will later be described. The cutter bar 2 is rigidly supported within the bed section 8 30 in planes adjacent the mine floor and extends rearwardly beneath the frame sections 11 and 12 within a chamber 13 formed within the bed section 8 and extending lengthwise 35 through the same. As illustrated, housed within the motor frame section 11 is a motor 14 of the type capable of driving the feeding and cutting mechanism selectively in opposite directions and is herein of the reversible, electric type having its power shaft 15 hori- 40 zontally disposed and extending longitudinally of the machine. Usual control apparatus of any approved design is provided for the motor 14 and herein includes a controller handle 16 and a reverse switch controlling lever 17.

Now referring to the driving mechanism for the cutter chain 3, it will be noted that suitably fixed as by a key and screw connection to the rear end of the motor shaft 15 is a 45 bevel pinion 18 meshing with a bevel gear 19 secured by a key 20 to a vertical shaft 21 disposed midway between the sides of the machine frame. This shaft is journaled at its upper end within a bearing 22 suitably supported within the upper part of the frame section 12 while the lower end of this shaft is journaled in a bearing 23 suitably supported within the bed section 8. As shown in Fig. 5, the shaft 21 has secured thereto a spur pinion 24 disposed below the bevel gear 19 and meshing with a large spur gear 25. This spur gear is secured by a key 26 to a vertical shaft 27 arranged parallel with and at the rear 50 of the shaft 21 and in the same longitudinally

extending vertical plane. As illustrated, the upper end of this shaft 27 is journaled in a bearing sleeve 28 suitably supported in the frame section 12 and the lower end of this shaft is journaled in a cup-shaped bearing 70 29 arranged within a bore 30 formed within an upstanding boss 31 herein formed integral with a detachable bottom plate 32 suitably secured to the bed section 8. A screw 33 is employed for adjustably securing the bearing member 29 to the detachable bottom plate 75 32. The bottom plate or shoe 9 is formed with an opening 34 which receives the detachable plate 32 and the bottom surface of this detachable plate is formed flush with 80 the plane bottom surface 10 of the shoe, thereby forming a smooth sliding supporting surface for the machine. Downward thrust of the spur gear 25 is received by a ball thrust bearing 36 held in position by the upper surface of the boss 31 and a top flange on the bearing member 29. Suitably secured to the hub of the spur gear 25 is an annular plate or ring 37 having an inwardly projecting flanged portion underlying the lower race of 90 the ball bearing 36 and an upstanding annular flange portion surrounding this ball bearing and projecting within a bore formed in the hub of the spur gear 25. As clearly shown in Fig. 5, surrounding the hub portion of the spur gear 25 and supported by the annular plate 37 secured to the gear is a bearing sleeve 38 rotatably supporting a cutter chain drive sprocket 39 which engages and drives the cutter chain 3 in a usual manner. Clutch mechanism of a usual design is employed for connecting this cutter chain drive sprocket 39 directly to the spur gear 25 for rotation therewith and herein comprises clutch pins 40 slidably mounted within bores 41 formed within the spur gear 25. These clutch pins when in their downward position (as shown in Fig. 5) are interlocked with clutch teeth 42 formed on the cutter chain sprocket 39. The clutch pins 40 are 100 herein formed integral with an annular member or ring 43 and cooperating with this ring are slidable lifting members 44 (see Figs. 8 and 9) arranged in bores 45 formed within the frame section 12 and having outwardly 105 projecting bottom flanges underlying the bottom surface of the ring. These members 44 carry pins 46 with which the arms of a shipper yoke 47 cooperate. This shipper yoke is pivotally mounted at 48 on the machine frame and has pivotally connected thereto at 49 a link 50 in turn pivotally connected at 51 to a crank or arm 52. This crank is keyed to a horizontal transversely 110 extending shaft 53 suitably rotatably mounted within the machine frame and having secured thereto at its outer end an operating lever 54 (see also Fig. 4). This lever has any usual spring-pressed locking means 55 for holding the same in its different adjusted po- 115 120 125 130

sitions. It will thus be seen that when the operator swings the lever 54 in the proper direction, the shipper yoke 47 is swung downwardly by the crank 52 and link connection 50, thereby sliding the members 44 and clutch pins 40 downwardly, connecting the latter with the clutch teeth 42 on the cutter chain sprocket and as a result this cutter chain drive sprocket is connected in driving relation with the motor 14. When this clutch is in its connected position as shown in Fig. 5, the cutter chain drive sprocket 39 may be driven from the motor through bevel gears 18, 19, vertical shaft 21, spur pinion 24 and the spur gear 25. The cutter chain may be disconnected from the motor at will simply by disconnecting the cutter chain drive sprocket from the spur gear 25.

Now referring to the improved feeding mechanism, it will be noted that improved separate driving and controlling means is provided for each winding drum whereby the drums may be rotated in winding direction either separately or simultaneously at a relatively slow speed or a relatively high speed, or may rotate in unwinding direction under various degrees of frictional resistance or without such resistance. As shown in the drawings, the vertical shaft 27 has clutched thereto at its upper end at 57 an aligned shaft 58 journaled in ball bearings 59 suitably supported in the frame section 12. As shown in Fig. 5, formed within the upper end of this shaft 58 is a bore 60 having a drive fit with a vertical stud 61. Supported by this stud is a spur pinion 62 connected by a jaw clutch 63 to the upper end of the vertical shaft 58. As shown in Fig. 4, meshing with this spur pinion 62 are spur gears 64 and 65 having their axes disposed in a common transverse vertical plane at opposite sides of the longitudinal vertical center of the machine (see also Fig. 7). These spur gears are supported on vertical studs 66 having drive fits with bores 67 formed within the upper ends of vertical shafts 68 and 69 respectively. The gears 64 and 65 are connected by jaw clutches 70 respectively to the upper ends of the shafts 68 and 69 and rotate with these shafts. These shafts are journaled at their opposite ends within ball bearings 71 and 72 suitably supported within the frame section 12, the latter bearings each being held in position by a retaining member 73. Disposed parallel with the shafts 68 and 69 at the opposite sides of the machine are vertical shafts 74 and 75 having their axes disposed in the same transverse vertical plane as the axes of the shafts 68 and 69. These shafts are journaled at their opposite ends in ball bearings 76 and 77 suitably supported within the frame section 12, the bearings 77 each being held in position by a retaining ring 78. Secured as by a key 79 to the lower end of each of

the shafts 74 and 75 respectively are spur gears 80 and 81 meshing with opposite sides of the spur gear 25, as clearly shown in Figs. 4 and 7. It will thus be seen that the shafts 68 and 69 are driven in the same direction at 70 a relatively slow speed by the vertical shaft 27 through the spur pinion 62 and spur gears 64 and 65, while the shafts 74 and 75 are driven in the same direction at a relatively high speed by the spur gears 80 and 81 meshing with the large spur gear 25 which also drives the cutter chain sprocket 39 as heretofore described.

Referring to the fast and slow speed driving connections for the feed drum 4 and more particularly to the slow speed driving connections therefor, it will be observed that formed integral with the vertical shaft 68 intermediate its ends is a worm 82 meshing with a worm wheel 83 having its hub portion at its inner side journaled in a ball bearing 84 suitably supported by a central bearing bracket suitably supported within the frame section 12 (see Fig. 4). The other side of this worm wheel is journaled on a ball bearing 85 supported by a horizontal shaft 86 extending transversely of the machine. The inner end of this shaft is journaled in a ball bearing 87 supported within the hub of the worm wheel while the other end of this shaft is journaled in a ball bearing 88 suitably supported within the side of the frame section 12. The worm wheel 83 is connectible by a friction disc clutch 89 of a usual design to a clutch member 90 keyed at 91 to the shaft 86. Suitably secured to the outer end of the shaft 86 is a spur pinion 92 meshing with an internal gear 93 connected to the feed drum 4. When the clutch 89 is applied, the feed drum 4 100 may be driven in winding direction from the motor 14 at a relatively slow speed through the bevel gearing 18, 19, spur gearing 24, 25, vertical shaft 27, spur pinion 62, spur gear 64, vertical shaft 68, worm 82, 110 worm wheel 83, shaft 86, spur pinion 92 and the internal gear secured to the drum.

The fast speed driving mechanism for the feed drum 4 comprises a worm 94 preferably formed integral with the vertical shaft 74 115 intermediate its ends, this worm having teeth of more inclination than the teeth of the worm 82 and is herein a fast speed worm. This worm 94 meshes with a worm wheel 95 having its inner hub portion journaled on a ball bearing 96 supported by the transverse shaft 86. The outer side of this worm wheel is journaled on a ball bearing 97 supported by the sleeve portion of a clutch member 98 keyed at 99 to the shaft 86. This worm wheel 95 is 120 connectible by a friction disc clutch 100 of a usual design to the clutch member 98 previously described. It will thus be seen that when the clutch 100 is applied the feed drum 4 may be driven in winding direction at a 125

relatively high speed in the same direction as the low speed described above through bevel gearing 18, 19, spur gearing 24, 25, spur gear 80, worm 94, worm wheel 95, shaft 86, spur pinion 92 and internal gear 93 secured to the drum 4. The operating mechanism for the friction clutches 89 and 100 comprises a clutch applying member 101 having an inwardly projecting flange projecting between and enclosing ball thrust bearings 102. These thrust bearings engage members 103 having inwardly projecting fingers projecting through the hub of the worm wheel into engagement with the adjacent end disc of the clutch discs. The clutch applying member 101 and the members 103 surround the adjacent hubs of the worm wheels and are slidably mounted thereon. The operating means for the clutch applying member 101 will be later described.

The fast and slow speed driving connections for the controlling drum 5 are substantially the same as the driving connections for the feed drum 4 with the exception that the drum 5 is driven in the opposite direction from that in which the drum 4 is driven and include a slow speed worm 104 secured to the vertical shaft 69 and meshing with a worm wheel 105. This worm wheel is connectible by a friction clutch 106 of a usual design to a clutch member 107 keyed to a transversely extending horizontal shaft 108 alined with the shaft 86 and disposed on the opposite side of the longitudinal center of the machine. Secured to the vertical shaft 75 is a fast speed worm 109 meshing with a worm wheel 110 connectible by a friction disc clutch 111 to a clutch member 112 also keyed to the shaft 108. The bearing structure for the worm wheels 105 and 110 and the shaft 108 is identical to that for the worm wheels 88 and 95 and the shaft 86 and therefore detailed description of the same is thought unnecessary. Suitably secured to the outer end of the shaft 108 is a spur pinion 113 meshing with an internal gear 114 connected to the winding drum 5. It will thus be seen that when the clutch 106 is applied, the winding drum 5 may be driven from the motor 14 in winding direction at a relatively slow speed through bevel gearing 18, 19, spur gear 24, 25, vertical shaft 27, spur gearing 62, 65, worm 104, worm wheel 105, shaft 108, spur pinion 113 and internal gear 114 secured to the drum 5. When the friction clutch 111 is applied, the winding drum 5 may be driven from the motor in a winding direction at a relatively high speed through bevel gearing 18, 19, spur gearing 24, 25, spur gear 81, worm 109, worm wheel 110, shaft 108, spur pinion 113 meshing with internal gear 114 secured to the drum 5. The applying means for the friction clutches 106 and 111 is identical to the operating means for the friction clutches 89 and 100 and includes a clutch applying member 115 similar to the

member 101. It will be noted that the friction clutches controlling the drive for either drum may be released sufficiently to permit the drums to rotate in unwinding direction to unwind the cables under various degrees of frictional resistance under the control of the clutch operating mechanism. Upon release of the friction clutches the drums may be entirely relieved from any frictional resistance due to the action of the friction clutches. As shown in Fig. 6, each of the winding drums 4 and 5 is journaled on the side of the machine frame on a laterally projecting stub shaft 116 formed integral with a plate 116^a secured as by screws 116^b to the side of the frame section 12. Supported on this shaft are ball bearings 117 on which the drum is journaled. Each of the winding drums is composed of two parts secured together by screws 118 and suitable dowel pins and is held from axial displacement from the shaft by means of a two-part or split sleeve 119 seated in a reduced portion on the shaft and engaging the inner races of the ball bearings. This two part sleeve is held in place by a retaining ring 120, and the complete bearing structure for each drum is disposed in a bore 121 within the drum. The opposite sides of the frame section 12 each have an annular flanged portion 122 encircling the internal gears 93 and 114 on the drums. These flanged portions each carry packing rings 123 engaging the external periphery of the internal gears and thereby prevent access of dirt or other foreign substances to the internal mechanism.

The operating mechanism for the clutch applying members 101 and 115, as shown in Fig. 10, comprises shipper yokes 124 and 125 engaging the members 101 and 115 respectively. As shown in Fig. 11, each of these shipper yokes is pivotally mounted at 126 within the frame section 12, and they are pivotally connected at 127 to trunnion members 128 and 129, respectively. The trunnion member 128 is in the form of a nut threadedly connected at 130 to a screw 131 formed integral with a hollow shaft 132. This shaft is journaled in a ball bearing 133 supported in the side of the frame section 12 and has clutch teeth 134 connectible to clutch teeth 135 carried by a clutch member secured to a horizontal shaft 136 extending centrally through the shaft 132 transversely of the rear end of the machine. Secured to this shaft 136 between its ends is an operating lever 137. The trunnion 129 connected to the shipper yoke 124 is threadedly connected to a screw formed on a shaft 138 similar to the shaft 132 and having clutch teeth similarly connectible to clutch teeth carried by the other end of the transverse shaft 136. It will thus be seen that when the operator grasps the lever 137 and shifts the shaft 136 in the proper direction, the clutch teeth 134, 135 are connected, thereby connecting the shaft 136 to the shaft 132 and upon rotation 130

of the shaft 136 the screw 131 is rotated, thereby moving the trunnion nut 128 axially to swing the shipper yoke 125 about its pivot, thereby applying one or the other of the friction clutches 106 and 111. It is obvious that when the shaft 136 is shifted in the opposite direction, the shaft 138 is connected to the shaft 136 and upon rotation of the shaft 136 in the proper direction, the trunnion nut 129 is moved axially by the screw, thereby swinging the shipper yoke 124 and applying one or the other of the friction clutches 89 and 100.

Improved guiding means is employed for the feed and controlling cables 6 and 7 and herein includes guide sheaves 140 and 141 disposed at opposite sides of the forward end of the machine frame, as clearly shown in Fig. 1. These guide sheaves are adjustably mounted on the frame of the machine in an improved manner and the adjustable mounting for each sheave comprises a swing arm 142 (see also Fig. 12) pivotally connected at 143 within a recess 144 formed within the side of the motor frame section 11. As illustrated, pivotally connected to the outer end of this swing arm 142 at 145 is a support member 146 carrying at its outer end a stud 147. Supported by the stud is a bearing sleeve 148 on which the guide sheave is journaled. It will thus be seen that with the parts in the position indicated by full lines in Fig. 12, the support 146 and the guide sheave may swing upwardly and downwardly about the pivot 145 to permit the cable to assume positions at different angles relative to the machine frame. The swing arm 142 is held in the full line position indicated in Fig. 12 by means of a locking pin 149 insertable within an aperture 150 formed within the swing arm 142. This pin, as shown in Fig. 13, is slidably mounted within a guide member 151 secured to the side of the machine frame. The outer end of this pin 149 is pivotally connected at 152 to an operating lever 153 pivoted at 154 on the side of the machine. When the parts are in the position shown in Fig. 13, the swing arm 142 is locked against swinging movement. When the locking pin 149 is released from the aperture 150 in the swing arm, the latter may be swung upwardly to the dotted line position shown in Fig. 12, and maintained in that position by the locking pin 149 underlying the swing arm. The support 146 for the guide sheave may be swung into its "out of the way" position against the side of the machine frame as indicated in dotted lines in Fig. 12. Disposed at the opposite rear corners of the machine frame are guide sheaves 155 and 156 each journaled as shown in Fig. 14 on a bearing sleeve 157 supported by a vertical stud 158 secured to a bracket 159 secured to the side of the frame section 12. Pivotally mounted at the lower end of each of the studs 158 at 160 is a cable retaining member 161 which prevents the cable, when slackened, from drop-

ping off the guide sheave. Arranged at the inner side of the guide sheaves 155 and 156 on inclined axes and supported by the brackets 159 are guide sheaves 162 and 163 while arranged between the sheaves 162 and 163 on similarly inclined axes are guide sheaves 164 and 165. Disposed on a vertical axis at the longitudinal vertical center of the machine is a guide sheave 166. When the machine is cutting from right to left, the feed cable 6 extends from beneath the feed drum 4 forwardly along the advancing side of the machine around the front guide sheave 140 and laterally of the machine. The controlling cable 7 extends from beneath the controlling drum 5 rearwardly along the rear side of the machine around the guide sheave 156 and laterally of the machine. The cable 6 is wound about the winding drum 4 in a direction opposite from that which the cable 7 is wound on the drum 5, but as these drums rotate in opposite directions, the cables are both drawn in by power. Either of the cables 6 and 7 may be extended from its drum upwardly around one of the inclined guide sheaves 162, 163, 90 downwardly beneath one of the inclined guide sheaves 164, 165 and around the central guide sheave 166 rearwardly from the rear end of the machine. When the machine is cutting from left to right the cables are reversely wound on their respective drums and the cable 7 extends from beneath the drum 5 forwardly around the guide sheave 141 and the cable 6 extends from beneath the drum 4 rearwardly around the guide sheave 155 as indicated in dotted lines in Fig. 1.

The mining machine is adapted to be supported on a transport truck in a well known manner and the mining machine motor 14 is adapted to drive the truck wheels. The truck driving means on the machine comprises a spur gear 167 meshing, as shown in Fig. 5, with the spur gear 25 and journaled on a bearing sleeve 168 supported by a vertical shaft 169 suitably secured within the frame section 12. This spur gear 167 is adapted to mesh with a truck driving gear on the transport truck and the mining machine motor 14 is adapted to drive the truck wheels through bevel gearing 18, 19, spur gearing 24, 25, and 115 the truck driving gear 167. As shown most clearly in Fig. 3, the frame 12 is cut away at 170 so as to clear the gear 167 and thereby permit the latter, as the machine is moved rearwardly onto its transport truck, to move 120 into meshing engagement with the usual truck driving gear.

The general mode of operation of the improved mining machine is as follows: The machine is transported about the mine while 125 supported on its transport truck, the truck wheels being driven from the mining machine motor 14 and when the working place is reached, the machine is unloaded from the truck onto the mine floor in a well known 130

manner. The cable 7 is then extended from beneath the controlling drum 5 rearwardly around the guide sheave 156, forwardly along the side of the machine, around the front 5 guide sheave 141 and forwardly from the machine to a suitable anchor or roof jack located adjacent the coal face at the right hand rib of the room. The friction clutch 111 within the fast speed worm wheel 110 is then applied and the drum 5 is driven in winding direction by the motor 14 at a relatively fast speed and as a result the controlling cable 7 is drawn in and the machine moved at a fast moving speed over the mine 10 floor. If desired, the feed cable 6 and feed drum 4 may be utilized to move the machine over the mine floor and under certain conditions both the cables 6 and 7 may be extended forwardly of the machine to suitable anchors or jacks adjacent the coal face to move the machine over the mine floor. After the machine has been suitably positioned adjacent the coal face at the right hand rib of the room, the clutch 111 is released and the controlling cable 7 is disconnected from the front 15 guide sheave 141 while still retaining its connection with the roof jack at the right hand rim. The feed cable 6 is then extended from beneath the feed drum 4 forwardly along the side of the machine, around the front guide sheave 140 and laterally from the machine 20 transversely across the coal face to a suitable anchor or roof jack located adjacent the coal face at the left hand rib of the room. The operator then manipulates the lever 54, thereby shifting the clutch pins 40 into interlocking relation with the clutch jaws 42 formed on the cutter chain driving sprocket 39, thereby connecting the cutter chain 3 in driving 25 relation with the motor 14, and as a result the cutter chain is rapidly circulated about the outer edges of the cutter bar 2. The friction clutch 106 within the slow speed worm wheel 105 is then applied and the drum 5 is driven in winding direction at a relatively 30 slow speed, thereby feeding the machine longitudinally to sump the cutter bar beneath the mine wall, the clutch 89 within the slow speed worm wheel 83 being so applied at that 35 time as to effect rotation of the feed drum 4 in winding direction at a slow speed to maintain a desired controlling tension on the feed cable 6 to guide the machine during its sumping movement. If desired, the feed cable 6 and feed drum 4 may be utilized to feed the machine longitudinally to effect sumping of the cutter bar beneath the coal. It will also be noted that if desired both the cables 6 and 40 7 may be extended to anchors adjacent the coal face and drawn in by the drums 4 and 5 to effect longitudinal movement of the machine at a sumping speed. After the sumping cut has been completed, the friction clutch 89 within the slow speed worm wheel 83 is then fully applied, thereby effecting rotation 45

of the feed drum 4 at a relatively slow speed in winding direction and as a result the machine is straightened up and fed transversely across the coal face to effect the transverse cut. During this transverse cutting operation the 50 friction clutch 106 within the slow speed worm wheel 105 is partially applied and the drum 5 is rotated at a slow speed in a direction to wind in the controlling cable 7, but due to the opposing forces caused by the pull 55 of the feed cable 6 on the forward end of the machine and the reaction of the cutters against the coal, the controlling cable 7 is pulled off the drum 5 under the frictional resistance of the friction clutch 106. If it is 60 desired during the transverse cutting operation to angle the cutter bar, the operator may release the controlling drum 5 from its drive, thereby permitting the drum to rotate freely and as a result the rear end of the machine 65 is swung forwardly due to the pull of the feed cable 6 on the front end of the machine frame. If it is desired to swing the cutter bar forwardly, this may be accomplished by applying the fast speed friction clutch 111 within 70 the worm wheel 110, thereby causing the controlling drum 5 to be rotated at a high speed in a direction to wind in the controlling cable 7, and resultantly swinging the rear end of the machine rearwardly and angling the 75 cutter bar. This can also be accomplished more slowly by more fully loading clutch 106. The cutter bar may be swung forwardly also by the application of the fast speed friction clutch 100 within the worm wheel 95 to cause 80 the feed drum 4 to wind in the feed cable 6 at a relatively high speed. At the end of the transverse cut the machine is angled relative to the coal face in a well known manner and the feed cable 6 is disconnected from its jack 85 and the front guide sheave 140 and extended from the feed drum 4 to an anchor or roof jack located at the rear of the machine. The feed drum 4 is then rotated in a direction to wind in the feed cable 6 at a relatively slow 90 speed thereby feeding the machine rearwardly, withdrawing the cutter bar from beneath the coal. The machine is then hauled over the mine bottom at a relatively high speed by one or the other, or both, of the feed cables 6 and 95 100 105 110 115 120 125 130 135 140 145 150 155 160 165 170 175 180 10120 10125 10130 10135 10140 10145 10150 10155 10160 10165 10170 10175 10180 10185 10190 10195 10200 10205 10210 10215 10220 10225 10230 10235 10240 10245 10250 10255 10260 10265 10270 10275 1

spective links and the feed cables wound about their respective drums in an opposite direction and extended from the sides of the machine in an opposite manner. The feed cable 6 also may be extended from beneath the feed drum 4 upwardly around the guide sheave 162, downwardly beneath the guide sheave 164 and around the central guide sheave 166 when the cable is reversely wound 10 on the drum. Other operations of the improved mining machine will be clearly apparent to those skilled in this art.

As a result of this invention it will be noted that an improved mining machine is provided having improved feeding mechanism whereby the machine may be fed and guided in an improved manner. It will further be noted that an improved mining machine feeding mechanism is provided wherein a plurality 20 of drums is employed and improved driving and controlling means for the drums whereby the latter may be rotated either separately or simultaneously in winding direction at relatively high speed or at relatively slow speed, may rotate in unwinding direction under various degrees of operator controlled frictional resistance, or may rotate freely in unwinding direction. It will further be noted that an improved room and pillar mining 25 machine is provided of exceedingly compact construction having improved feeding mechanism of a symmetrical, well balanced and compact design, the driving connections between the motor and each of the drums being substantially identical in construction and operation.

While there is in this application specifically described one form which the invention may assume in practice, it will be understood 40 that this form of the same is shown for purposes of illustration and that the invention may be modified and embodied in various other forms without departing from its spirit or the scope of the appended claims.

45 What I claim as new and desire to secure by Letters Patent is:

1. In a mining machine, a motor and feeding means driven by said motor including relatively rotatable feed operating and controlling members disposed on axes parallel to a transverse vertical plane and each adapted to cooperate with flexible feeding means, and separate fast and slow speed driving connections between said motor and each of 55 said members entirely distinct from the drive for the other member, the driving connections for each member including parallel worms and coaxial worm wheels meshing therewith.

60 2. In a mining machine, a motor and feeding means driven by said motor including relatively rotatable feed operating and controlling members disposed on axes parallel to a transverse vertical plane and each adapted to cooperate with flexible feeding means,

and separate fast and slow speed driving connections between said motor and each of said members entirely distinct from the drive for the other member, the driving connections for each member including parallel worms and coaxial worm wheels meshing therewith and a separate friction controlling clutch for connecting each worm wheel in driving relation with its respective member. 70

3. A mining machine feeding mechanism including relatively rotatable feed members disposed on axes parallel to a transverse vertical plane and each adapted to cooperate directly with flexible feeding means, and motor operated driving means for said members including a separate and distinct plural speed transmission mechanism for each member whereby said members may be driven either separately or simultaneously at relatively low speed or at a relatively high speed, each of said transmission mechanisms including a fast speed gear train and a slow speed gear train, an element of each gear train rotating about a vertical axis. 75

4. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at a relatively high speed, each of said transmission mechanisms including a fast speed gear train and a slow speed gear train, and a gear train of each mechanism including an element rotating about a vertical axis and a common driving member for said elements and rotating about a parallel axis. 80

5. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at a relatively high speed, each of said transmission mechanisms including a fast speed gear train and a slow speed gear train, and each gear train having an element rotating about a vertical axis, and a common driving element for said elements of one gear train in the drive for both members and rotating about a parallel axis. 85

6. A mining machine feeding mechanism including relatively rotatable feed members disposed on axes parallel to a transverse vertical plane and each adapted to cooperate directly with flexible feeding means, and motor operated driving means for said members including a separate and distinct plural speed transmission mechanism for each 90

member whereby said members may be driven either separately or simultaneously at relatively low speed or at relatively high speed, each of said transmission mechanisms including a fast speed worm gear train and a slow speed worm gear train, and each gear train including a worm rotating about a vertical axis.

7. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at relatively high speed, each of said transmission mechanisms including a fast speed worm gear train and a slow speed worm gear train, each gear train including a worm rotating about a vertical axis, and common driving gearing for the worms of one gear train in the drive for both of said members.

8. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at relatively high speed, each of said transmission mechanisms including a fast speed worm gear train and a slow speed worm gear train, each gear train including a worm rotating about a vertical axis, common driving gearing for the worms of one gear train in the drive for both of said members, and separate and distinct driving gearing for said other worms.

9. A mining machine feeding mechanism including relatively rotatable feed members disposed on axes parallel to a transverse vertical plane and each adapted to cooperate directly with flexible feeding means, and motor operated driving means for said members including a separate and distinct plural speed transmission mechanism for each member whereby said members may be driven either separately or simultaneously at relatively low speed or at relatively high speed, and each of said transmission mechanisms including a fast speed worm gear train and a slow speed worm gear train, each of said trains including a worm and all of the worms of said trains rotating on parallel axes.

10. A mining machine feeding mechanism including relatively rotatable feed members disposed on axes parallel to a transverse vertical plane and each adapted to cooperate directly with flexible feeding means, and

motor operated driving means for said members including a separate and distinct plural speed transmission mechanism for each member whereby said members may be driven either separately or simultaneously at relatively high speed or at relatively low speed, and each of said transmission mechanisms including a fast speed worm gear train and a slow speed worm gear train, and each of said trains including a worm and said worms rotating on parallel vertical axes.

11. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at relatively high speed, each of said transmission mechanisms including a fast speed gear train and a slow speed gear train, a driving gear rotatable about a vertical axis and driving gears meshing therewith, and connected respectively to a gear train in the drive for each member.

12. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at relatively high speed, each of said transmission mechanisms including a fast speed gear train and a slow speed gear train, one gear train for each member including a gear rotating about a vertical axis, gears respectively connected to said gears, and a common driving gear meshing with said last mentioned gears.

13. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively low speed or at relatively high speed, each of said transmission mechanisms including a fast speed gear train and a slow speed gear train, one gear train for each member including a gear rotating about a vertical axis, gears respectively connected to said gears, and a common driving gear meshing with said last mentioned gears and rotating about a vertical axis.

14. A mining machine feeding mechanism including relatively rotatable feed members

- disposed on axes parallel to a transverse vertical plane and each adapted to cooperate directly with flexible feeding means, and motor operated driving means for said members
- 5 including a fast speed gear train and a slow speed gear train for one member, a separate and distinct fast speed gear train and a slow speed gear train for said other member, the fast speed gear trains for both members including driving gears rotatable about parallel axes and the slow speed gear trains for both members including driving gears rotatable about parallel axes, a gear driving both of said gears of said fast speed gear 70
- 10 gear trains, and another gear driving both of said gears of said slow speed gear trains, said driving gears rotating about vertical axes.
- 15 15. A mining machine feeding mechanism including relatively rotatable feed members disposed on axes parallel to a transverse vertical plane and each adapted to cooperate directly with flexible feeding means, and motor operated driving means for said members including a fast speed gear train and a slow speed gear train for one member, a separate and distinct fast speed gear train and a slow speed gear train for said other member, the fast speed gear 75
- 20 gear trains for both members each including a driving gear rotatable about a vertical axis.
- 25 16. A mining machine feeding mechanism including relatively rotatable feed members disposed on axes parallel to a transverse vertical plane and each adapted to cooperate directly with flexible feeding means, and motor operated driving means for said members including a fast speed gear train and a slow speed gear train for one member, a separate and distinct fast speed gear train and a slow speed gear train for said other member, the fast speed gear 80
- 30 gear trains for both members including gears rotating about vertical axes, the slow speed gear trains for both members including gears rotating about vertical axes, a driving gear meshing with said gears of said fast speed gear trains and a driving gear meshing with said gears of said slow speed gear trains.
- 35 17. A mining machine feeding mechanism including relatively rotatable feed members disposed on axes parallel to a transverse vertical plane and each adapted to cooperate directly with flexible feeding means, and motor operated driving means for said members including a fast speed gear train and a slow speed gear train for one member, a separate and distinct fast speed gear train and a slow speed gear train for said other member, the fast speed gear 85
- 40 gear trains for both members including driving gears rotatable about parallel axes laterally offset from but parallel with the axes of said first mentioned driving gears.
- 45 18. A mining machine feeding mechanism including relatively rotatable feed members disposed on axes parallel to a transverse vertical plane and each adapted to cooperate directly with flexible feeding means, and motor operated driving means for said members including a fast speed gear train and a slow speed gear train for one member, a separate and distinct fast speed gear train and a slow speed gear train for said other member, the fast speed gear 90
- 50 gear trains for both members including driving gears rotatable about parallel axes, a gear driving both of said gears of said fast speed gear trains, and another gear driving both of said gears of said slow speed gear trains.
- 55 19. A mining machine feeding mechanism including relatively rotatable feed members each adapted to cooperate directly with flexible feeding means, and motor operated driving means for said members including a fast speed gear train and a slow speed gear train for one member, a separate and distinct fast speed gear train and a slow speed gear train for said other member, the fast speed gear 95
- 60 gear trains for both members including gears rotating about vertical axes, the slow speed gear trains for both members including gears rotating about vertical axes, a driving gear meshing with said gears of said fast speed gear trains, and a driving gear meshing with said gears of said slow speed gear trains, said driving gears being coaxially arranged.
- 65 20. A mining machine feeding mechanism including relatively rotatable feed members each adapted to cooperate directly with flexible feeding means, and motor operated driving means for said members including a fast speed gear train and a slow speed gear train for one member, a separate and distinct fast speed gear train and a slow speed gear train for said other member, the fast speed gear 100
- 70 gear trains for both members including gears rotating about vertical axes, a driving gear meshing with said gears of said fast speed gear trains, and a driving gear meshing with said gears of said slow speed gear trains, said driving gears being coaxially arranged.
- 75 21. A mining machine feeding mechanism including relatively rotatable feed members each adapted to cooperate directly with flexible feeding means, and motor operated driving means for said members including a fast speed gear train and a slow speed gear train for one member, a separate and distinct fast speed gear train and a slow speed gear train for said other member, the fast speed gear 105
- 80 gear trains for both members including gears rotating about vertical axes, the slow speed gear trains for both members including gears rotating about vertical axes, a driving gear meshing with said gears of said fast speed gear trains, and a driving gear meshing with said gears of said slow speed gear trains, said driving gears being coaxially arranged.
- 85 22. A mining machine feeding mechanism 110

- 110
- 115
- 120
- 125
- 130

including relatively rotatable feed members each adapted to cooperate directly with flexible feeding means, and motor operated driving means for said members including a shaft, 3 gears coaxial therewith, separate slow speed gear trains driven by one of said gears for driving said members respectively, and separate fast speed trains driven by said other coaxial gear and respectively driving said 10 feed members.

23. A mining machine feeding mechanism including relatively rotatable feed members each adapted to cooperate directly with flexible feeding means, and motor operated driving 15 means for said members including a vertical shaft, gears coaxial therewith, separate slow speed gear trains driven by one of said gears for driving said members respectively, and separate fast speed trains driven by said 20 other coaxial gear and respectively driving said feed members.

24. A mining machine feeding mechanism including relatively rotatable feed members each adapted to cooperate directly with flexible 25 feeding means, and motor operated driving means for said members including a shaft, gears coaxial with said shaft at the opposite ends thereof, a fast speed gear train and a slow speed gear train for one member and a 30 fast speed gear train and a slow speed gear train for said other member, the slow speed gear trains for said members being operatively connected to the gear at one end of said shaft and the fast speed gear trains for said 35 members being operatively connected to the gear at the opposite end of said shaft.

25. A mining machine feeding mechanism including relatively rotatable feed members disposed on axes parallel to a transverse vertical 10 plane and each adapted to cooperate directly with flexible feeding means, and motor operated driving means for said members whereby said members may be driven either separately or simultaneously at relatively 15 high speed or at relatively low speed and including a separate and distinct plural pre-determined speed transmission mechanism for each member, each of said transmission mechanisms including coaxial worm wheels, 20 worms meshing respectively therewith and rotating on parallel axes, and manually controllable clutches for selectively connecting said worm wheels in driving relation with their respective members.

26. A mining machine feeding mechanism including relatively rotatable feed members disposed on axes parallel to a transverse vertical plane and each adapted to cooperate directly with flexible feeding means, and motor 25 operated driving means for said members whereby said members may be driven either separately or simultaneously at relatively high speed or at relatively low speed and including a separate and distinct plural pre-determined speed transmission mechanism 30

for each member, each of said transmission mechanisms including coaxial worm wheels, worms meshing respectively therewith and rotating on parallel vertical axes, and manually controllable clutches for selectively connecting said worm wheels in driving relation with their respective members. 70

27. In a mining machine, cutting mechanism including a kerf cutter and driving means therefor including a gear, and feeding means including relatively rotatable feed members each adapted to cooperate directly with flexible feeding means and motor operated driving means for said members whereby said members may be driven either separately or simultaneously at relatively high speed or at relatively low speed and including a separate and distinct plural predetermined speed transmission mechanism for each member whereby said members may be driven either separately or simultaneously at fast or slow speeds, said transmission mechanisms both being driven by said kerf cutter driving gear and each including a gear element meshing with said gear. 75 80 85 90

28. In a mining machine, cutting mechanism including a kerf cutter and driving means therefor including a gear, and feeding means including relatively rotatable feed members each adapted to cooperate directly with flexible feeding means and motor operated driving means for said members including separate fast and slow speed gear trains for each member whereby said members may be driven either separately or simultaneously at fast or slow speeds, one of said gear trains for each member having a gear meshing with and driven by said kerf cutter driving gear, and said other gear trains for said members including a driving element coaxial with said kerf cutter driving gear. 95 100 105

29. In a mining machine, cutting mechanism including a kerf cutter and driving means therefor including a gear, and feeding means including relatively rotatable feed members each adapted to cooperate directly with flexible feeding means and motor operated driving means for said members including separate fast and slow speed gear trains for each member whereby said members may be driven either separately or simultaneously at fast or slow speeds, one of said gear trains for each member having a gear meshing with and driven by said kerf cutter driving gear, a shaft driven by said kerf cutter driving gear, and the other gear trains for said members being driven by said shaft. 110 115 120

30. In a mining machine, cutting mechanism including a kerf cutter and driving means therefor including a gear, and feeding means including relatively rotatable feed members each adapted to cooperate directly with flexible feeding means and motor operated driving means for said members including separate fast and slow speed gear 125 130

trains for each member, said fast speed gear trains for both members each having a gear meshing with and driven by said kerf cutter driving gear, a shaft driven by said kerf cutter driving gear, and driving connections between said shaft and said slow speed gear trains.

31. A mining machine feeding mechanism including relatively rotatable feed members each adapted to cooperate directly with flexible feeding means, and motor operated driving means for said members including coaxial driving gears rotating about an axis lying in a vertical plane extending transversely of the machine, a fast speed gear train for each member, each including a gear meshing with and driven by one of said coaxial gears and a slow speed gear train for each member each including a gear meshing with and driven by said other coaxial gear.

32. A mining machine feeding mechanism including relatively rotatable feed members each adapted to cooperate directly with flexible feeding means, and motor operated driving means for said members including coaxial driving gears rotating about a vertical axis, a fast speed gear train for each member, each including a gear meshing with and driven by one of said coaxial gears and a slow speed gear train for each member each including a gear meshing with and driven by said other coaxial gear.

33. In a mining machine, cutting mechanism including a kerf cutter and driving means therefor including a driving gear, and feeding means for the machine driven by said kerf cutter driving gear and including relatively rotatable feed members disposed on axes parallel to a transverse vertical plane and each adapted to cooperate directly with flexible feeding means and driving mechanism for said members including a separate and distinct plural speed transmission mechanism for each member whereby said members may be driven either separately or simultaneously at relatively high speed or at relatively low speed each transmission mechanism including a fast speed gear train and a friction controlling clutch and a slow speed gear train having a separate friction controlling clutch.

34. In a mining machine, cutting mechanism including a kerf cutter and driving means therefor including a driving gear, and feeding means for the machine driven by said kerf cutter driving gear and including relatively rotatable feed members disposed on axes parallel to a transverse vertical plane and each adapted to cooperate directly with flexible feeding means and driving mechanism for said members including a separate and distinct plural speed transmission mechanism for each member whereby said members may be driven either separately or simultaneously at relatively high speed or at

relatively low speed, each transmission mechanism including a fast speed worm gear train and a slow speed worm gear train.

35. In a mining machine, cutting mechanism including a kerf cutter and driving means therefor including a driving gear, and feeding means for the machine driven by said kerf cutter driving gear and including relatively rotatable feed members disposed on axes parallel to a transverse vertical plane and each adapted to cooperate directly with flexible feeding means and driving mechanism for said members including a separate and distinct plural speed transmission mechanism for each member whereby said members may be driven either separately or simultaneously at relatively high speed or at relatively low speed, each transmission mechanism including a fast speed worm gear train and a slow speed worm gear train and each gear train including a final worm wheel and manually controllable friction clutches for selectively connecting said worm wheels in driving relation with their respective members.

36. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of acting as a feed member and a controlling member, said members being disposed on axes parallel to a transverse vertical plane and each adapted to cooperate directly with flexible feeding means, and a separate and distinct multi-speed driving mechanism for each member and both driven by said transmission element and operative to drive said members either separately or simultaneously in a direction to draw in their respective flexible feeding means at relatively high speed or at relatively low speed, each driving mechanism including a fast speed friction controlling clutch and a slow speed friction controlling clutch.

37. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of acting as a feed member and a controlling member, said members being disposed on axes parallel to a transverse vertical plane and each adapted to cooperate directly with flexible feeding means, and a separate and dis-

tinct multi-speed driving mechanism for each member and both driven by said transmission element and operative to drive said members either separately or simultaneously in 5 a direction to draw in their respective flexible feeding means at relatively high speed or at relatively low speed or to permit said members to revolve in a direction to pay out their respective flexible feeding means under 10 various degrees of frictional resistance, each driving mechanism including a fast speed friction controlling clutch and a slow speed friction controlling clutch.

38. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of 20 acting as a feed member and a controlling member, said members being disposed on axes parallel to a transverse vertical plane and each adapted to cooperate directly with flexible feeding means, and a separate and distinct multi-speed driving mechanism for each 25 member and both driven by said transmission element and operative to drive said members either separately or simultaneously in a direction to draw in their respective flexible feeding means at relatively high speed or at relatively low speed or to permit said members to revolve in a direction to pay out their 30 respective flexible feeding means under various degrees of frictional resistance, each driving mechanism including coaxial fast and slow speed terminal gears and friction controlling clutches one individual to each 35 gear.

39. In a mining machine, cutting mechanism including a kerf cutter and driving means therefor including a motor shaft and a transmission element driven thereby, and feeding means including relatively rotatable feeding members of the same size and diameter and rotatable at like peripheral speeds 40 both at a relatively fast predetermined moving speed and a relatively slow predetermined cutting speed, and either capable of acting as a feed member and a controlling member, said members being disposed on horizontal axes extending transversely of the machine and each adapted to cooperate directly with flexible feeding means, and a separate and distinct multi-speed driving mechanism for each member and both driven by said transmission element and operative to drive said members either separately or 45 simultaneously in a direction to draw in their respective flexible feeding means at relatively high speed or at relatively low speed or to permit said members to revolve in a direction to pay out their respective flexible feeding means under various degrees of frictional resistance, each driving mechanism including coaxial fast and slow speed terminal gears and friction controlling clutches one individual to each 50 gear.

40. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of acting as a feed member and a controlling member, said members being disposed on horizontal axes extending transversely of the machine and each adapted to cooperate directly with flexible feeding means, and a separate and distinct multi-speed driving mechanism for each member and both driven by said transmission element and operative to drive said members either separately or simultaneously in a direction to draw in their respective flexible feeding means at relatively high speed or at relatively low speed, each driving mechanism 55 including coaxial fast and slow speed terminal gears and friction controlling clutches one individual to each gear.

41. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of 60 acting as a feed member and a controlling member, said members being disposed on horizontal axes extending transversely of the machine and each adapted to cooperate directly with flexible feeding means, and a separate and distinct multi-speed driving mechanism for each member and both driven by said transmission element and operative to drive said members either separately or simultaneously in a direction to draw in their respective flexible feeding means at relatively high speed or at relatively low speed or to permit said members to revolve in a direction to pay out their respective flexible feeding means under various degrees of frictional resistance, each driving mechanism including coaxial fast and slow speed terminal gears and friction controlling clutches one individual to each gear.

42. A mining machine feeding mechanism including relatively rotatable feed members each adapted to cooperate directly with flexible feeding means, and motor operated driv-

nism including coaxial fast and slow speed terminal gears.

40. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of acting as a feed member and a controlling member, said members being disposed on horizontal axes extending transversely of the machine and each adapted to cooperate directly with flexible feeding means, and a separate and distinct multi-speed driving mechanism for each member and both driven by said transmission element and operative to drive said members either separately or simultaneously in a direction to draw in their respective flexible feeding means at relatively high speed or at relatively low speed or to permit said members to revolve in a direction to pay out their respective flexible feeding means under various degrees of frictional resistance, each driving mechanism including coaxial fast and slow speed terminal gears and friction controlling clutches one individual to each gear.

41. In a mining machine, cutting mechanism including a kerf cutter and driving means therefor including a motor shaft and a transmission element driven thereby, and feeding means including relatively rotatable feeding members of the same size and diameter and rotatable at like peripheral speeds both at a relatively fast predetermined moving speed and a relatively slow predetermined cutting speed and either capable of acting as a feed member and a controlling member, said members being disposed on horizontal axes extending transversely of the machine and each adapted to cooperate directly with flexible feeding means, and a separate and distinct multi-speed driving mechanism for each member and both driven by said transmission element and operative to drive said members either separately or simultaneously in a direction to draw in their respective flexible feeding means at relatively high speed or at relatively low speed or to permit said members to revolve in a direction to pay out their respective flexible feeding means under various degrees of frictional resistance, each driving mechanism including coaxial fast and slow speed terminal gears and friction controlling clutches one individual to each gear.

42. A mining machine feeding mechanism including relatively rotatable feed members each adapted to cooperate directly with flexible feeding means, and motor operated driv-

- ing means for said members for rotating the latter either separately or simultaneously in a direction to draw in their respective flexible feeding means at relatively high speed or at relatively low speed including four coaxial 5 worm wheels, two individual to each member, and four worms rotating on parallel axes and meshing with said worm wheels respectively.
43. A mining machine feeding mechanism 10 including relatively rotatable feed members each adapted to cooperate directly with flexible feeding means, and motor operated driving means for said members for rotating the latter either separately or simultaneously in a direction to draw in their respective flexible 15 feeding means at relatively high speed or at relatively low speed including four coaxial worm wheels, two individual to each member, four worms rotating on parallel axes and meshing with said worm wheels respectively, and clutch devices for selectively connecting said worm wheels in driving relation with said feeding members.
44. A mining machine feeding mechanism 20 including relatively rotatable feed members each adapted to cooperate directly with flexible feeding means, and motor operated driving means for said members for rotating the latter either separately or simultaneously in a direction to draw in their respective flexible 25 feeding means at relatively high speed or at relatively low speed including a vertical shaft, a gear connected with said shaft and driving the same, separate and distinct fast speed driving connections for said members each including a gear meshing with said gear, and separate and distinct slow speed 30 driving connections for said members operatively connected to said shaft.
45. A mining machine feeding mechanism 35 including relatively rotatable feed members each adapted to cooperate directly with flexible feeding means, and motor operated driving means for said members for rotating the latter either separately or simultaneously in a direction to draw in their respective flexible feeding means at relatively high speed or at relatively low speed including coaxially 40 arranged gears, separate and distinct slow speed driving connections between one of said gears and each of said members, and separate and distinct fast speed driving connections between said other coaxial gear and each of said feed members.
46. A mining machine feeding mechanism 45 including relatively rotatable feed members disposed on horizontal axes extending transversely of the machine and each adapted to cooperate directly with flexible feeding means, and motor operated driving means for said members for driving said members either separately or simultaneously at relatively high speed or at relatively low speed 50 including alined shafts one connected to each member, and a separate and distinct plural predetermined speed transmission mechanism for each shaft, each of said transmission mechanisms including a fast speed gear train and a slow speed gear train, an element of each gear train rotating about a 55 vertical axis.
47. A mining machine feeding mechanism 60 including relatively rotatable feed members disposed on horizontal axes extending transversely of the machine and each adapted to cooperate directly with flexible feeding means, and motor operated driving means for said members for driving said members either separately or simultaneously at relatively high speed or at relatively low speed including alined shafts one connected to each member, and a separate and distinct plural speed transmission mechanism for each shaft, each transmission mechanism including a fast speed worm wheel and a slow speed worm 65 wheel, and worms rotating on laterally spaced, parallel axes and meshing with said worm wheels respectively.
48. In a mining machine, cutting mechanism 70 including a kerf cutter and driving means therefor including a large spur gear, feeding means including relatively rotatable feed members each adapted to cooperate directly with flexible feeding means, and driving means driven by said gear, and including gears meshing directly with the latter, for rotating said members either separately or simultaneously in a direction to draw in their 75 respective flexible feeding means at relatively high speed or at relatively low speed, and truck driving mechanism including a final spur gear on the machine meshing directly with said kerf cutter driving gear.
49. A mining machine feeding mechanism 80 including relatively rotatable feed members each adapted to cooperate directly with flexible feeding means, and motor operated driving means for said members for rotating said members either separately or simultaneously in a direction to draw in their 85 respective flexible feeding means at relatively high speed or at relatively low speed and including a separate and distinct plural speed transmission mechanism for each member, said mechanisms including four shafts each of which is parallel to all the others, gears driven by said shafts respectively, and clutch devices for connecting said gears in driving relation with their respective members.
50. In a mining machine, cutting mechanism 90 including a kerf cutter and driving means therefor including a motor shaft and a transmission element driven thereby, and feeding means for the machine including relatively rotatable feed operating and controlling members of the same size and diameter and rotatable at like peripheral speeds both at a relatively fast predetermined moving speed and a relatively slow predetermined speed.

mined cutting speed and either capable of acting as a feed member and a controlling member, said members being disposed on axes parallel to a transverse vertical plane and each adapted to cooperate directly with flexible feeding means, and motor operated driving means for said feeding members driven through said kerf cutter driving element, and including for each member fast and slow speed transmission mechanism through which it, but not the other member, is driven and each transmission mechanism including fast and slow speed gear trains and friction controlling clutches one individual to each gear train.

51. In a mining machine, cutting mechanism including a kerf cutter and driving means therefor including a motor shaft and a transmission element driven thereby, and feeding means including relatively rotatable feed operating and controlling members of the same size and diameter and rotatable at like peripheral speeds both at a relatively fast predetermined moving speed and a relatively slow predetermined cutting speed and either capable of acting as a feed member and a controlling member, said members each being adapted to cooperate directly with flexible feeding means, and motor operated driving means for said members driven through said kerf cutter driving element for driving said members either separately or simultaneously in a direction to draw in their respective flexible feeding means at a relatively high predetermined speed or at a relatively low predetermined speed, and including for each member fast and slow predetermined speed transmission mechanism through which it, but not the other member, is driven and each transmission mechanism including fast and slow speed gear trains and friction controlling clutches one individual to each gear train.

52. A mining machine feeding mechanism including relatively rotatable feed members each adapted to cooperate directly with flexible feeding means, and motor operated driving means for said members including coaxial gears rotatable at the same angular rate and of different diameters, separate gear trains between one of said coaxial gears and said feed members respectively for driving said members at one speed, and separate gear trains between the other of said coaxial gears and said feed members for driving the latter at a relatively different speed.

53. A mining machine feeding mechanism including relatively rotatable feed members each adapted to cooperate directly with flexible feeding means, and motor operated driving means for said members including coaxial gears rotatable at the same angular rate and of different diameters, separate gear trains between one of said coaxial gears and said feed members respectively for driving said

members at one speed, separate gear trains between the other of said coaxial gears and said feed members for driving the latter at a relatively different speed, and clutch devices, one individual to each gear train, for controlling the connection of said gear trains with their respective feed members. 70

54. In a mining machine, cutting mechanism including a kerf cutter and driving means for said kerf cutter including a gear rotatable about a vertical axis, and feeding means for the machine including relatively rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said last mentioned gear and said feeding members respectively for driving the latter at a relatively different speed. 75

55. In a mining machine, cutting mechanism including a kerf cutter and driving means for said kerf cutter including a gear rotatable about a vertical axis, and feeding means for the machine including relatively rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said last mentioned gear and said feeding members respectively for driving the latter at a relatively different speed, each of said gear trains including a spur gear rotating about 80

100 a vertical axis. 105

56. In a mining machine, cutting mechanism including a kerf cutter and driving means for said kerf cutter including a gear rotatable about a vertical axis, and feeding means for the machine including relatively rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said last mentioned gear and said feeding members respectively for driving the latter at a relatively different speed, each of said gear trains including a gear rotating about a vertical axis, and a clutch controlling the connection of said gears with their respective members. 110

57. In a mining machine, cutting mechanism including a kerf cutter and driving means for said kerf cutter including a gear rotatable about a vertical axis, and feeding 115

120

- means for the machine including relatively rotatable feeding members each adapted to cooperate directly with flexible feeding means, separate gear trains meshing with 5 said kerf cutter driving gear and driven thereby for driving said feeding members at one speed, a vertical shaft driven by said kerf cutter driving gear, a gear secured to said shaft, and separate gear trains between said 10 last mentioned gear and said feeding members respectively for driving the latter at a relatively different speed, each of said gear trains including a worm and a worm wheel meshing therewith. 15 58. In a mining machine, cutting mechanism including a kerf cutter and driving means for said kerf cutter including a gear rotatable about a vertical axis, and feeding means for the machine including relatively 20 rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said 25 last mentioned gear and said feeding members respectively for driving the latter at a relatively different speed, each of said gear trains including a worm and a worm wheel meshing with said worm, and said worm 30 wheels being arranged in coaxial relation. 62. In a mining machine, cutting mechanism including a kerf cutter and driving means for said kerf cutter including a gear rotatable about a vertical axis, and feeding 35 means for the machine including relatively rotatable feeding members each adapted to cooperate directly with flexible feeding means, separate gear trains meshing with said kerf cutter driving gear and driven thereby 40 for driving said feeding members at one speed, a vertical shaft driven by said kerf cutter driving gear, a gear secured to said shaft, and separate gear trains between said 45 last mentioned gear and said feeding members respectively for driving the latter at a relatively different speed, each of said gear trains including a worm rotating about a vertical axis and a worm wheel meshing with said worm, and said worm wheels being ar- 50 ranged in coaxial relation. 63. In a mining machine, cutting mechanism including a kerf cutter and driving means for said kerf cutter including a gear rotatable about a vertical axis, and feeding 55 means for the machine including relatively rotatable feeding members each adapted to cooperate directly with flexible feeding means, separate gear trains meshing with said kerf cutter driving gear and driven thereby 60 for driving said feeding members at one speed, a vertical shaft driven by said kerf cutter driving gear, a gear secured to said shaft, and separate gear trains between said 65 last mentioned gear and said feeding members respectively for driving the latter at a relatively different speed, each of said gear trains including a worm and a worm wheel meshing with said worm, and said worm 70 wheels being arranged in coaxial relation. 75 59. In a mining machine, cutting mechanism including a kerf cutter and driving means for said kerf cutter including a gear rotatable about a vertical axis, and feeding 80 means for the machine including relatively rotatable feeding members each adapted to cooperate directly with flexible feeding means, separate gear trains meshing with said kerf cutter driving gear and driven thereby 85 for driving said feeding members at one speed, a vertical shaft driven by said kerf cutter driving gear, a gear secured to said shaft, and separate gear trains between said 90 last mentioned gear and said feeding members respectively for driving the latter at a relatively different speed, each of said gear trains including a worm and a worm wheel meshing with said worm, and said worm 95 wheels being arranged in coaxial relation. 100 60. In a mining machine, cutting mechanism including a kerf cutter and driving means for said kerf cutter including a gear rotatable about a vertical axis, and feeding 105 means for the machine including relatively rotatable feeding members each adapted to cooperate directly with flexible feeding means, separate gear trains meshing with said kerf cutter driving gear and driven thereby 110 for driving said feeding members at one speed, a vertical shaft driven by said kerf cutter driving gear, a gear secured to said shaft, and separate gear trains between said 115 last mentioned gear and said feeding members respectively for driving the latter at a relatively different speed, each of said gear trains including a worm rotating about a vertical axis and a worm wheel meshing with said worm, and said worm wheels being ar- 120 ranged in coaxial relation. 125 65. In a mining machine, cutting mechanism including a kerf cutter and driving means for said kerf cutter including a gear rotatable about a vertical axis, and feeding 130 means for the machine including relatively rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said last mentioned gear and said feeding members respectively for driving the latter at a relatively different speed, each of said gear trains including a worm and a worm wheel meshing with said worm, and said worm wheels being arranged in coaxial relation on

horizontal axes extending transversely of the machine.

64. In a mining machine, cutting mechanism including a kerf cutter and driving means for said kerf cutter including a gear rotatable about a vertical axis, and feeding means for the machine including relatively rotatable feeding members each adapted to cooperate directly with flexible feeding means, separate gear trains meshing with said kerf cutter driving gear and driven thereby for driving said feeding members at one speed, a vertical shaft driven by said kerf cutter driving gear, a gear secured to said shaft, and separate gear trains between said last mentioned gear and said feeding members respectively for driving the latter at a relatively different speed, each of said gear trains including a worm rotating about a vertical axis and a worm wheel meshing with said worm, and said worm wheels being arranged in coaxial relation on horizontal axes extending transversely of the machine.

In testimony whereof I affix my signature.
